PADDLE-BOARD

Harry H. Hollington, Gardena, Calif., assignor to Aeroplastics Corporation, El Segundo, Calif., a corporation of California

Application April 21, 1959, Serial No. 55,602

Term of patent 14 years

(Cl. D71—1)

Fig. 1

Fig. 2

Fig. 3

Fig. 4

Figure 1 is a top plan view of a paddle-board showing my new design;

Figure 2 is a bottom plan view;

Figure 3 is a front elevational view; and

Figure 4 is a side elevational view.

I claim:

The ornamental design for a paddle-board, substantially as shown.
